UNITED STATES PATENT OFFICE.

DAVID NEUVERT, OF HERINGTON, KANSAS.

CONCRETE-TILE MANUFACTURING MACHINE.

Application filed August 24, 1927. Serial No. 215,165.

This invention relates to concrete tile and block manufacturing machines, and its general object is to provide a machine that will form tile and the like in a dense and compact manner, with maximum amount of water and with minimum tamping.

A further object of the invention is to provide a concrete tile manufacturing machine including means whereby the tile can be easily and expeditiously removed therefrom without removing or collapsing the form.

Another object of the invention is to provide a machine of the character set forth, that can be used for making various sizes of tile by merely changing the size of the form and compacting former.

A still further object of the invention is to provide a tile manufacturing machine that is simple in construction, inexpensive to manufacture and efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a vertical sectional view taken through the machine forming the subject matter of the present invention and showing parts thereof in elevation.

Figure 2 is a top plan view.

Figure 3 is a sectional view taken approximately on line 3—3 of Figure 1.

Figure 4 is a perspective view of the stripper.

Referring to the drawings in detail, the reference numeral 1 indicates the base of the machine, which is hollow as shown and has arranged therein a cross member 2. Secured intermediate the ends of the cross member upon its upper surface is a bearing block 3 having journaled therein a shaft 5 which has one end extending through the base and mounted in a bearing 6 secured to one side of the base as clearly shown in Figure 1 of the drawings.

The top wall of the base has centrally depending therefrom a bearing 7 having passing therethrough a shaft 8 which is vertically disposed and arranged at right angles

with respect to the shaft 5. The shaft 8 extends through the cross member 2 and has secured to its lower end through the instrumentality of a set screw, a collar 9. Secured to this shaft 8 and disposed in the base is a gear 10 which is arranged in mesh with a pinion 11 fixed to the inner end of the shaft 5 while secured to the outer end of said shaft 5 is a pulley 12.

Arranged upon the top of the base and held secured thereto through the medium of bolts 13 passing through apertured ears 14 formed with the bottom thereof is the form 15 of the machine which I have shown as being square in cross section. The form 15 is provided with an opening disposed in its bottom for the passage of the shaft 8, and this shaft has secured to its upper end and rising therefrom a compacting former 16 arranged in the form 15 for cooperation with the walls thereof for compacting concrete and the like disposed between the former and said walls. The compacting former is substantially oval shape in cross section its entire length.

A stripper of the type as shown in Figure 4 is provided for lifting the tile or blocks from the form 15, and this stripper includes a supporting plate 17 provided with a circular opening 18 and rising from the supporting plate is a pair of oppositely disposed uprights 19 having their upper ends bent at right angles upon themselves to provide handles 20.

From the above description and disclosure of the drawings, it will be apparent that I have provided a tile and block manufacturing machine that is extremely simple in construction and when it is desired to form a block, the stripper is disposed in the form 15 as shown in Figure 1, the block forming material is poured between the compacting former and walls of the form, and the machine is put into operation by the application of a belt or other suitable means to the pulley, such belt or means being operated from any suitable source of power. When the block has been sufficiently packed, it can be removed by the stripper.

Different sizes of blocks can be formed by changing the sizes of the form and compacting former as these members are detachable as will be apparent.

It is thought from the foregoing description that the advantages and novel features of my invention will be readily apparent.

I desire it to be understood that I may

make changes in the construction and in the combination and arrangement of the several parts, provided that such changes fall within the scope of the appended claims.

5. What I claim is:

1. A machine of the character described comprising a base, a concrete form secured to and rising from said base, a compacting former mounted for rotation in said form, 10 means for rotating said compacting former, and a stripper detachably arranged in said form about said compacting former.
2. A machine of the character described comprising a base, a form rising from said 15 base, means for detachably securing the form to said base, a compacting former mounted for rotation in said form, a shaft secured to said compacting former and depending therefrom, means for rotating said shaft 20 for rotating the compacting former accordingly, a stripper including a supporting plate having an opening therein to accommodate 25 said compacting former, uprights rising from said supporting plate and handles formed with said uprights.

3. A machine of the character described

comprising a base, a form detachably secured to said base, a compacting former mounted for rotation in said form and being substantially oval shape in cross section, means for 30 rotating said compacting former and a stripper detachably arranged in said form and provided with an opening to accommodate the compacting former.

4. A concrete tile and block making machine comprising a base, a cross member arranged in said base, a bearing supported by said cross member, a shaft mounted in said bearing and projecting through the base, a pulley secured through the projecting end 40 of said shaft, a pinion secured to the opposite end of said shaft, a shaft disposed at right angles to the shaft first mentioned and projecting through the top of said base, a gear secured to the shaft projecting through 45 the top of said base and meshing with the pinion, a form detachably secured to and rising from the top of said base, a compacting former arranged in said form and secured to the last mentioned shaft, and a 50 stripper removably arranged in said form.

DAVE NEUVERT.
